UNITED STATES PATENT OFFICE.

VICTOR LOUGHEED, OF SANTA BARBARA, CALIFORNIA, ASSIGNOR TO DUODISK STEEL WHEEL CORPORATION, OF LOS ANGELES, CALIFORNIA, A CORPORATION OF DELAWARE.

DISK-WHEEL ASSEMBLY.

1,379,352.

Specification of Letters Patent. Patented May 24, 1921.

Application filed November 26, 1920. Serial No. 426,546.

To all whom it may concern:

Be it known that I, VICTOR LOUGHEED, a citizen of the United States, residing at Santa Barbara, in the county of Santa Barbara and State of California, have invented 5 certain new and useful Improvements in Disk-Wheel Assemblies, of which the following is a specification.

This invention relates to metal wheels 10 built up from a hub, a rim, and a web connecting the hub and the rim, and particularly to the construction of the web and the manner of assembling it with the hub whereby the web is better adapted to transmit 15 the load from the hub to the rim and maintain more secure connection with the hub.

The invention consists in constructing the web of a plurality of disks, fixedly related 20 in an annulus remote from the hub but spaced apart and movably related at their centers or place of section with the hub, but there provided with means for clamping them firmly and solidly against a hub part, 25 a suitable filler being introduced between the disks at the place of clamping, and the disks being given a firm or permanent set which normally holds them slightly away from their spacing fillers when unclamped, 30 but within reach of said fillers under the clamping action without exceeding their elastic limits; so that when clamped the disks are left under initial strains in the direction of resistance to the load which they 35 are to carry; and bolts, which are preferably used for the clamping means, will be locked against unscrewing by the resiliency of the disks in opposition to the clamping pressure; and, if preferred, one or more of 40 the disks can be brought into radial bearing upon the barrel of the hub and given an initial firm pressure thereon by distortion incident to the clamping action.

The invention will be fully understood 45 upon reference to the accompanying drawing, in which—

Figures 1, 2, and 3 represent in axial section three embodiments of the invention.

In each of the figures A represents the 50 hub having a flange B and a barrel C, and D represents the web which carries the rim

E and is clamped to the hub between the clamping plate F and the flange B through the medium of bolts G having nuts g. Web D is composed of two disks d and d' in Figs. 55 1 and 3, and three disks, d, d', and d² in Fig. 2. The disks which compose the web are fixedly related in an annulus remote from the hub, for instance, at the inner circumference H of the rim E in Figs. 1 and 2, 60 and at the intermediate resilient zone K and also at the rim circumference H in Fig. 3, to which the disks extend in the divergent annular portions d⁴ and d⁴¹ and which widens their rim-receiving base. 65

The disk d in each of the figures is preferably brought into radial bearing upon the barrel C of the hub as indicated at d⁵. To maintain the bearing of the disk upon the hub when the disk is deflected, by the clamping action hereinafter referred to the inner edge of the disk is rolled axially outward. In Fig. 2 the intermediate disk d² is likewise brought into radial bearing upon the barrel of the hub as suggested at d⁵¹, the 70 hub barrel at such point being coned to continue the bearing as the disk is distorted by the clamping operation. In Fig. 3 the disk d is provided in an annulus just beyond the clamping zone with an additional 75 deflection or swell d⁶ which lends to this disk a radial resiliency greater than that of the disk d'. It will be noted that the disk of increased radial resiliency is the one which is stepped directly upon the barrel of 80 the hub at d⁵. It will further be noted that in Fig. 3 portions of the disks lying, respectively, within and beyond the resilient zone K have received two distinct dishings, or a reverse dishing in each disk, which condition also increases radial resiliency and 85 co-acts beneficially with the condition of distortion of the disks under the clamping operation and loading them with initial strains. 90

While the drawing indicates no spacing between the filler block and the end disk next to the hub flange, it will be understood that axial stress imposed upon the companion disk will be transmitted at the annulus of fixed relation (the circumference of the rim in Figs. 1 and 2, and the resilient 95 100

zone K in Fig. 3), and this will transmit a portion of the load to the end disk until they are equalized.

In each of the forms the disks are spaced 5 apart at the center, where they are received by the hub, through the medium of the filler block I (Figs. 1 and 3) or the divided filler block I, I' (Fig. 2). In each of the forms the disks are dished and given an original 10 form or permanent set which causes them to space themselves apart a distance slightly greater than that measured by the thickness of their filler blocks, as suggested by the dotted and full lines in the figures, so that 15 when clamped tightly between the plate F and the flange B, by drawing up their clamping bolts G, the disks will be put under initial strains in the direction of the load which they are to bear in use, and they will 20 be better adapted to stand up under loads imposed upon them. These strains, in the disks d , d' in each form, will be of compression, since a pressing of these disks toward each other tends to flatten out their dishing, 25 and this is resisted by the rim. The intermediate disk d^2 in Fig. 2, if given a substantially flat form in its original set, will be slightly dished in the clamping operation and put under strains of tension. It will 30 thus be seen that the kind of initial strains imposed upon the disks may be determined by the initial form imparted to the disk and the form to which it will be distorted under the clamping operation. It will also be seen 35 that since the disks constantly oppose the clamping operation by their resiliency in seeking to return to their normal shapes, frictional pressure will be maintained at all times against the nuts g which will effectively lock them against unscrewing.

I claim:

1. In a demountable disk wheel, a hub having a radial clamping flange; a web-member constructed for radial bearing upon the hub and axial abutment against its flange, comprising resilient disks fixedly united in an annulus radially remote from the hub, and initially held yieldingly spaced apart adjacent to the hub; filling means 45 between the yieldingly spaced portions of the disks, of less axial dimension than the distance between the disks; and bolts releasably clamping the web to the hub-flange, passing through and deflecting the disks, drawing them together upon the filling means and holding the clamped parts under 50 stress.

2. In a demountable disk wheel, a rim-member; a hub having a radial clamping flange; a web member comprising disks fixedly united together in an annulus radially remote from the hub and also united to the rim member radially beyond said annulus, and initially held in radially spaced relation 55

adjacent to the hub; filling means interposed 65 between the portions of the disks so spaced, having a radial dimension less than the distance therebetween; and bolts releasably clamping the web to the hub-flange, and drawing the disks together upon the filling 70 means; a disk being of resilient structure, and being held under stress by the bolts.

3. In a demountable disk wheel, a hub having a radial clamping flange; a web-member constructed for radial bearing upon 75 the hub and axial abutment against its flange, comprising resilient disks fixedly united in an annulus radially remote from the hub, and initially held yieldingly spaced apart adjacent to the hub; filling means be- 80 tween the yieldingly spaced portions of the disks, of less axial dimension than the distance between the disks; and bolts releasably clamping the web to the hub-flange, passing through and deflecting the disks, drawing 85 them together upon the filling means and holding the clamped parts under stress; a deflected disk having an outwardly rolled inner edge through which it is in direct bearing 90 upon the hub.

4. In a demountable disk wheel, a hub having a radial clamping flange; a web-member constructed for radial bearing upon the hub and axial abutment against its flange, comprising resilient disks fixedly 95 united in an annulus radially remote from the hub, and initially held yieldingly spaced apart adjacent to the hub; filling means be- 100 tween the yieldingly spaced portions of the disks, of less axial dimension than the distance between the disks; and bolts releasably clamping the web to the hub-flange, passing through and deflecting the disks, drawing them together upon the filling means and holding the clamped parts under 105 stress; the disk remote from the hub-flange being in direct bearing upon the hub and having an annular swell between said annulus and its bearing portion.

5. In a demountable disk wheel, a hub having a radial clamping flange; a web-member constructed for radial bearing upon the hub and axial abutment against its flange, comprising resilient disks fixedly 110 united in an annulus radially remote from the hub, and initially held yieldingly spaced apart adjacent to the hub; filling means between the yieldingly spaced portions of the disks, of less axial dimension than the distance between the disks; and bolts re- 115 leasesably clamping the web to the hub-flange, passing through and deflecting the disks, drawing them together upon the filling means and holding the clamped parts under 120 stress; the disks being dished in the same axial direction, but with different degrees of curvature.

6. In a demountable disk wheel, a rim-

member, a hub having a radial clamping flange; and a web-member clamped to said hub; said web-member comprising a pair of dished disks having fixedly united coinciding faces in an annulus radially remote from the hub and being extended beyond said annulus to the rim and there deflected to provide rim-receiving flanges extending both in the same axial direction and in the same circumference, with the flange on one disk abutting the other disk.

Signed at San Francisco, California, this 8th day of November, 1920.

VICTOR LOUGHEED.
